UNITED STATES PATENT OFFICE.

WILLIAM C. BURGUM, OF PITTSBURG, PENNSYLVANIA, ASSIGNOR OF ONE-HALF TO HARVEY H. FRANCIES, OF PITTSBURG, PENNSYLVANIA.

BRICK-MACHINE.

SPECIFICATION forming part of Letters Patent No. 738,406, dated September 8, 1903.

Application filed January 2, 1903. Serial No. 137,595. (No model.)

To all whom it may concern:

Be it known that I, WILLIAM C. BURGUM, a citizen of the United States, residing at Pittsburgh, in the county of Allegheny and State of Pennsylvania, have invented certain new and useful Improvements in Brick-Machines, of which the following is a specification, reference being had therein to the accompanying drawings.

10 This invention relates to improvements in brick-machines, and more particularly to a new and improved attachment for brick-machines.

The object of the invention is to provide 15 new and improved means for cutting and removing the surplus clay in the molds after the brick-forms have been passed through the brick-machine—that is to say, after the clay is pressed within the molds in the usual 20 manner and the molds containing the clay have been released from said pressure the clay expands a certain amount and it is necessary in order to form perfect bricks to cut and remove the clay which projects from said 25 molds. Heretofore, so far as I am aware, this has been done by manual labor.

In the accompanying drawings, which illustrate an application of my invention, Figure 1 is a perspective view of an apparatus constructed in accordance with my invention; 30 Fig. 2, a side elevational view particularly showing the manner the knife and mold pushing-bars are operated; Fig. 3, a detail of pushing-bar or "kicker;" Fig. 4, a detail view 35 of knife and a portion of one of the two slotted rails; and Fig. 5, detail view of a portion of the knife and casting.

Referring to the drawings, the apparatus as illustrated is mounted on two posts 1 and is 40 located slightly above the brick-machine table 2. The distance the apparatus is located above the table 2 depends on the height of the molds 3. An actuating-lever 4, designed to be connected with the crank-arm (not 45 shown) of the brick-machine or other suitable means for operating said bar, is pivotally connected with a bent rod 5 by means of a coupling member 6. Bent rod 5 extends downwardly through a cross-piece 7 and is

connected at its lower end with cross guide- 50 rod 8. Cross-piece 7 has its bearings in blocks 9, suitably secured to posts 1.

An angular knife 10 is carried on pins 11, which latter are suspended in movable rods 12. These movable rods 12 are each provided 55 with a reduced portion 13, located in and adapted to travel up and down in holes cut through cross-piece 7 as the knife is carried to move over the molds. The upward and downward movement of said rods is controlled 60 by the nuts 14 and the shoulders 15, and the rods are guided by means of the guide-rod 8. At both ends of the knife on the pins 11 I provide a casting comprising a collar 16, journal 17, and a circular slide 18. Slide 18 65 is provided with a projection 19, which is arranged to enter slots 20, formed in the rails 21, which latter are suitably attached to the posts 1. Extending downwardly from cross-piece 7 and extending to the rear of the knife 70 are two pushing-rods or kickers 22. The function of these rods is to move the molds forward, as particularly shown by Fig. 2. 23 are braces for the pushing-rods and connect 75 said rods with guide-rods 8.

In practice as the molds are delivered from the press onto the table one mold pushes the one immediately in advance of it forward, and for the purpose of permitting the pushing-rods 22 to act upon the mold at the proper 80 time the table is provided with slightly-inclined tracks, as shown at 24 in Fig. 1 of the drawings.

Attention is called to the fact that the surplus clay in the molds is not removed by 85 starting the knife or scraper at the rear of the mold and passing the same forward to the front, but is started to operate at about the middle or slightly less than the middle. Were the knife or scraper started at the rear end 90 and moved forward, the clay would be drawn away from the rear of the mold and an imperfect brick would be formed.

The position of the parts as illustrated by Fig. 1 is such as they assume just prior to 95 operating on the clay. Raising the coupling member 6 by means of the lever 4 causes the knife to be turned over into the position shown

by Fig. 2. This is accomplished by reason of the projection 19, on the circular slide 18, coming in contact with the end of the slot 20. This turns the pins 11, on which the knife is mounted, thereby bringing the knife into the desired operative position. Continuing the pull on the coupling member 6 causes the knife to travel over the mold and the mold to be pushed forward to the position shown by dotted lines in Fig. 2. When the slide 18, with its projection 19, reaches the forward end of the rails 21, said projection 19 falls into slot 20, thus causing the knife to turn over and to assume a position for removing during the return travel of the knife the surplus clay not removed during the forward travel of the same over the mold.

What I claim is—

1. In an attachment for brick-machines, the combination with a table, a movable knife arranged to travel over molds located on the table, a cross-piece, means for supporting the cross-piece, oscillating and vertically-movable rods for supporting the knife and means for actuating the knife, substantially as set forth.
2. In an attachment for brick-machines, the combination with a table, a movable knife arranged to travel over molds located on the table, a cross-piece, means for supporting the cross-piece, oscillating and vertically-movable rods for supporting the knife, a pusher

attached to the cross-piece, and means for actuating the knife, substantially as set forth.

3. In an attachment for brick-machines, the combination with a table, a movable knife arranged to travel over molds located on the table, a cross-piece, means for supporting the cross-piece, oscillating and vertically-movable rods for supporting the knife, a slotted track, means carried with the knife arranged to travel on the track and to enter the slots in the track whereby the knife is brought into operative positions, and means for actuating the knife, substantially as set forth.

4. An attachment for brick-machines, comprising a frame, a table, a movable knife arranged to travel over molds located on the table, a slotted track, means carried with the knife arranged to travel on the track and to enter the slots in the track whereby the knife is caused to assume an operative position about midway of the molds on its travel in one direction over the molds and caused to be turned and to assume an operative position about midway of the molds upon the return movement of the knife, and means for actuating the knife, substantially as set forth.

In testimony whereof I affix my signature in presence of two witnesses.

WILLIAM C. BURGUM.
